UNITED STATES PATENT OFFICE.

FRANK McCORMICK, OF MONROE, WASHINGTON.

STUMP-EXTRACTOR.

1,169,503.

Specification of Letters Patent. Patented Jan. 25, 1916.

Application filed September 26, 1914. Serial No. 863,784.

To all whom it may concern:

Be it known that I, FRANK McCORMICK, a citizen of the United States, residing at Monroe, in the county of Snohomish and State of Washington, have invented certain new and useful Improvements in Stump-Extractors, of which the following is a specification, reference being had to the accompanying drawings.

10 This invention relates to certain improvements in stump extractors; and the object of the invention is to provide a novel and improved device of this general character of a portable nature so as to be easily moved from point to point, and comprising novel and improved means for the development of great power with a minimum of exertion.

15 The invention consists in the details of construction and in the combination and arrangement of the several parts of my improved stump extractor whereby certain important advantages are attained and the device is rendered simpler, less expensive 20 and otherwise more convenient and advantageous for use, all as will be hereinafter more fully set forth.

25 The novel features of the invention will be carefully defined in the appended claim.

30 In order that my invention may be the better understood, I will now proceed to describe the same with reference to the accompanying drawings, wherein—

35 Figure 1 is a view in top plan of a stump pulling device constructed in accordance with an embodiment of my invention: Fig. 2 is a sectional view taken substantially on the line 2—2 of Fig. 1; Fig. 3 is a front elevational view of the device as herein embodied: Fig. 4 is a sectional view taken substantially on the line 4—4 of Fig. 1; Fig. 5 is an enlarged fragmentary view in plan of a central portion of the sweep as herein embodied; and Fig. 6 is a detail view of a 40 fulcrum pin herein embodied.

45 As disclosed in the accompanying drawings, 1 denotes a bottom series of elongated parallel beams in predetermined transverse spaced relation and having superimposed 50 therein a second series of elongated transverse beams 2 and the adjacent extremities of said beams 1 and 2 are tied or connected by the transverse beams 3 interposed therebetween and in a manner which is believed 55 to be clearly obvious.

The outer beams 1 are provided along

their outer marginal portions with the depending runners 4 whereby the device may be readily transported from one locality to the other as the requirements of 60 practice may dictate. The beams 1 and 2 are provided with the elongated alined longitudinally spaced openings 5 through which the removable fulcrum pin 6 is 65 adapted to be directed, the head of such pin being provided with a loop 7 whereby the same may be manipulated with convenience and facility. In order to reinforce or strengthen the beams 1 and 2 against the strain imposed upon the fulcrum pin 6, as 70 will be hereinafter more fully set forth, I find it of advantage to provide the opposed faces of the beams 1 and 2 with the longitudinally directed metallic straps 8 provided with the openings 9 adapted to register with 75 the openings 5, hereinbefore referred to.

80 In order to brace the intermediate portions of the braces 1 and 2 against lateral strain, I find it of advantage to dispose through adjacent beams the inclined brace rods 9. In practice, I find it of advantage to have the brace rods 9 of adjacent beams disposed on such inclines as to intersect intermediate the beams and to have the various bracing structures disposed in stag- 85

gered relation, as by this arrangement I have found that greater rigidity and strength results. Adapted to be disposed between the beams 1 and 2 is a sweep 10 of predetermined length and herein dis- 90 closed as having its rear face provided with a reinforcing strip 11 of metal and having the longitudinal central portion of its rear face provided with spaced lugs 12 between which is adapted to be disposed the anchor- 95

100 ing pin 14 of the forwardly directed clevis 15. The clevis 15 is adapted to have detachably engaged therewith and preferably through the medium of a hook member 16 an extremity of a flexible member 17 which is adapted to be disposed through an opening 18 produced in the forward transverse member 3 and be suitably secured to the stump or the like to be extracted. In order that the sweep 10 may be further reinforced 105 against the strain or pressure imposed thereon during the extracting or pulling operation, I find it of advantage to have embedded within the rear face of the sweep at its central portion a metallic block 19 110 serving in a manner which is believed to be clearly apparent. The forward face of the

sweep 10 at opposite sides of its longitudinal center is provided with series of spaced lugs 20 which are adapted to receive therebetween a fulcrum pin 6.

5 I do not wish to be limited as to the character of power to be employed in connection with the sweep, although it will be readily understood that motor power may be employed with equal facility as draft animals.

10 In order that the device may be suitably anchored so as to permit the operation thereof, I secure to the opposite side faces of the rear extremities of the outer beams 1 the plates 21 having disposed therethrough 15 the pins 22 whereby the clevises 23 may be operatively engaged therewith. Any suitable means may be employed to coact with the clevises for anchoring the device to a stationary support, although I find in practice it is best to employ flexible members as indicated in fragment at 24.

From the foregoing description, it is thought to be obvious that a stump extractor constructed in accordance with my 25 invention is of an extremely simple and comparatively inexpensive nature and is particularly well adapted for use by reason of the convenience and facility with which

it may be assembled, and it will also be obvious that my invention is susceptible of 30 some change and modification without material departure from the principles and spirit thereof and for this reason I do not wish to be understood as limiting myself to the precise arrangement and formation 35 of the several parts herein shown in carrying out my invention in practice.

I claim:

A device of the character described comprising a base member, a removable fulcrum 40 coacting with the base, a sweep, spaced lugs carried by the sweep adapted to receive the fulcrum therebetween, the face of the sweep opposite to the lugs being provided with a reinforcing strip and having spaced lugs 45 projecting therefrom, the portion of the sweep immediately adjacent the last named lugs having a metallic block embedded therein.

In testimony whereof I hereunto affix my 50 signature in the presence of two witnesses.

FRANK McCORMICK.
